[57] **CLAIM**

The ornamental design for a cursor control, as shown and described.

DESCRIPTION

FIG. 1 is a perspective view of a cursor control showing my new design;

FIG. 2 is a top plan view of the cursor control;

FIG. 3 is a bottom plan view of the cursor control;

FIG. 4 is an elevational view of one end of the cursor control;

FIG. 5 is an elevational view of the other end of the cursor control;

FIG. 6 is an elevational view of one side of the cursor control; and

FIG. 7 is an elevational view of the other side of the cursor control.

The broken lines of a power cord in FIG. 1 are for illustrative purposes only.
